(57) **CLAIM**

The ornamental design for a ceiling lamp, as shown and described.

DESCRIPTION

Figure 1.0 is a front perspective view of an embodiment of a ceiling lamp showing my new design;

Figure 2.0 is a front perspective view of a second embodiment of a ceiling lamp; and

Figure 3.0 is a front perspective view of a third embodiment of a ceiling lamp.

The broken lines in the drawings depict portions of the ceiling lamp that form no part of the claim.
